(57) **CLAIM**

The ornamental design for a nozzle, as shown and described.

DESCRIPTION

FIG. 1 is a front perspective view of a nozzle showing our design.

FIG. 2 is a rear perspective of the nozzle in FIG. 1.

FIG. 3 is a front elevation view of the nozzle in FIG. 1.

FIG. 4 is a rear elevation view of the nozzle in FIG. 1.

FIG. 5 is a left side elevation view of the nozzle in FIG. 1.

FIG. 6 is a right side elevation view of the nozzle in FIG. 1.

FIG. 7 is a top plan view of the nozzle in FIG. 1.

FIG. 8 is a bottom plan view of the nozzle in FIG. 1; and, FIG. 9 is an enlarged view thereof, taken from portion 9 in FIG. 4.

The even-broken lines in the figures show portions of the nozzle that form no part of the claimed design. The dot-dash broken lines in FIG. 4 and FIG. 9 are included to identify the enlarged views and form no part of the claimed design.

1 Claim, 9 Drawing Sheets
